CLAIM

The ornamental design for a cutting tool insert, as shown and
described.

DESCRIPTION

FIG. 1 is a front view of a cutting tool insert in accordance
with an embodiment of the present design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a cross sectional view taken along line 9-9 of FIG.
1;

FIG. 10 is an enlarged view of portion 10 of FIG. 9; and,
FIG. 11 shows a cutting tool insert in an environment of use
thereof.

The broken lines shown in the drawings represent portions
of the cutting tool insert that form no part of the claimed
design.
